UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF WEST VIRGINIA.

APPARATUS FOR DRYING MATRICES.

1,121,265.

Specification of Letters Patent.

Patented Dec. 15, 1914.

Original application filed February 5, 1906, Serial No. 299,439. Divided and this application filed January 3, 1911. Serial No. 600,395.

To all whom it may concern:

Be it known that I, HENRY A. WISE Wood, a citizen of the United States, residing at New York, in the county of New York and State of New York, have invented a new and useful Apparatus for Drying Matrices, of which the following is a specification.

This is a division of my application for patent on method of drying matrices filed 10 Feb. 5, 1906, Serial No. 299,439.

The ordinary stereotype matrix is made by pressing a moist flong upon a form of type, and drying the matrix in contact with the type so that a hard, baked, reverse impression thereof is obtained. This drying of 15 the matrix in contact with the type takes a considerable period of time, sometimes five or six minutes in newspaper practice. The time thus consumed is of the utmost importance in newspaper work.

I have found that the drying of the matrix can be materially accelerated by holding the moist matrix in contact with the type by means of an absorbent material pressed 20 against the matrix and by withdrawing or exhausting the air from around the matrix, type, and absorbent material.

The invention consists of an improved form of apparatus for practising the method 25 here described.

The apparatus and modifications thereof are illustrated in the accompanying drawing; referring to which,

Figure 1 is an elevation partly in section 30 of enough of a matrix drying apparatus to illustrate how the same may be constructed to embody my invention; Fig. 2 is an elevation partly in section of a modification; and Fig. 3 is a perspective view of the preferred 35 form of chase.

Referring to the drawing and in detail, A designates the steam-table of an ordinary matrix drying press. This steam-table is usually made hollow and is sometimes arranged 40 on top of a connected boiler, or it may have steam otherwise supplied to its interior so as to present a hot upper surface to the form which lies upon it. An inclosing vacuum chamber B is arranged on top of said table and secured thereto by a tight joint. Extending above said vacuum chamber 45 is a yoke in which is formed or secured a pressure cylinder C. Fitting in the cylinder

C is a piston 10 which has a piston-rod 11 which extends down through a stuffing-box 55 12 formed in the top of the chamber B. The chamber may be formed with an air-tight door D.

Working in the chamber is a platen E which cooperates with the table A. The 60 face or bearing surface of the platen E is provided with small holes or perforations e. The platen is secured on the end of the piston-rod 11. The piston-rod 11 is provided with an abutment 13 at its end which works 65 in a small cylinder 14, a spring 15 being arranged under the abutment normally to raise the platen E. A steam or pressure pipe 16 connects with the cylinder C, and by admitting pressure into said cylinder C the platen 70 is forced down toward the table A. When the pressure is relieved the platen is lifted by the spring 15 from the table A. This means is shown for operating the platen, although, so far as the scope of my invention 75 is concerned, any suitable means may be used for operating the platen.

A pipe 17 is connected to the chamber B and to an exhaust pump G which may be driven by an electric motor H.

The chase which is usually employed is preferably perforated along its sides and ends as shown in Fig. 3. The side stick 30 and the foot stick 31 used in the chase are also preferably perforated, as indicated in 85 Fig. 3.

To make and dry a matrix the flong is laid upon the form of type and rolled into it. The chase containing the form with the matrix upon it is placed on the table A and 90 in the chamber B by sliding the same in through the door D. Upon the moist matrix is then placed one or more layers of dry blankets. The door D is then closed, and the platen brought down on top of the 95 matrix, holding the same in close contact with the type. As this operation takes place, the pump is driven to withdraw the air from the chamber B, and the moisture exuding or driven off from the matrix and 100 blankets by the heat is rapidly vaporized and carried away, and the matrix will be dried in much quicker time than by the old method of drying under atmospheric pressure.

In Fig. 2 a modification is shown which is

preferred for some purposes. In this arrangement the vacuum chamber B is made separate from the table A and is fitted to the piston-rod 11, a spring 20 being arranged 5 between the yoke and the top of the chamber B. In this arrangement the chamber is provided with a suitable packing 21 along its bottom. In this arrangement the pipe communicating with the interior of the 10 chamber is made in flexible form. In this modification when the platen is raised the chamber B is lifted up from the table so that the form of type may be slid in under the same with the matrix and blankets applied. When in position the platen E is forced 15 down. This will bring the chamber in contact with the table, and will close it, the continued downward movement of the platen bringing the same into contact with 20 the blankets, and the spring 20 holding the chamber in contact with the table. When the chamber is closed the air is exhausted and the previously described operation of drying is carried out.

25 Other forms of apparatus may be worked out for practising my invention without departing from the scope of my invention as expressed in the claims.

Having thus fully described my invention, 30 what I claim and desire to secure by Letters-Patent is:—

35 1. A matrix drying press comprising a heating table, a platen above the table, a chamber resting on the table and inclosing the platen but spaced therefrom all around its edges, means for exhausting the air in

the chamber around the platen, and means extending into the chamber for moving the platen therein.

2. A matrix drying press comprising a 40 heating table, a platen for pressing a matrix against the table, a chamber contacting with the table at its edges and inclosing the platen but spaced therefrom all around the edges of the platen, means for exhausting 45 the air from the chamber around the platen, said platen being perforated to permit the exhausting means to take the air from the matrix, and means extending into the chamber for reciprocating the platen therein. 50

3. A matrix drying press comprising a platen and table, a rod for operating the platen, a chamber mounted on said rod, a spring for depressing said chamber, and means for exhausting said chamber. 55

4. A matrix drying press comprising a platen and table, a chamber inclosing the platen, a stuffing-box in said chamber, a rod passing through said stuffing-box and connected to the platen for operating the same, 60 packing between the edge of the chamber and the table, and means for exhausting the air from said chamber and from all around the platen and matrix.

In testimony whereof I have hereunto set 65 my hand, in the presence of two subscribing witnesses.

HENRY A. WISE WOOD.
